ASH RECEIVER

Filed March 29, 1947

UNITED STATES PATENT OFFICE

2,605,772

ASH RECEIVER

Ernest J. Sweetland, Piedmont, Calif., assignor
to Sweetland Development Company, San
Francisco, Calif., a partnership

Application March 29, 1947, Serial No. 738,101

2 Claims. (Cl. 131—235)

1

This invention relates to a device for use in vehicles, and comprises an automatic means for extinguishing and disposing of cigarettes by the use of a simple mechanism which is actuated by the motion of the vehicle.

A further object of the invention is to provide for the automatic disposal of burnt matches, ashes, and similar discarded waste matter, in a manner that is simple and automatic and eliminates the fire risk that arises from the careless disposal of cigarette-ends, burnt matches, and the like.

A further object is to provide a simple form of ash receiver having a rotatable ash-receiving element which discharges into a closed receptacle that is sealed by said rotatable element to prevent the escape of smoke or odors from the receptacle.

A further object is to provide ash-receiving means for vehicles in the form of a cylinder with peripheral cavities, which is concealed within a wall of the vehicle when not in use, and which may be withdrawn from the wall to expose said cylinder when desired; the cavities being self-discharging upon rotation of said cylinder.

While certain forms of the apparatus contain moving parts, they are energized by the movement of the vehicle, and do not require attention, or the application of energy from any external source, as will be understood from the following description and the accompanying drawings in which:

Fig. 1 is a side elevation of the invention with a portion broken away to illustrate the internal mechanism.

Fig. 2 is a plan view of Fig. 1.

Fig. 3 is a side elevation of a modified form of wheel which may be substituted for the wheel 12 of Figs. 1 and 2.

Fig. 4 is an end elevation of Fig. 3.

Fig. 5 is a side elevation, partially in section, showing a receptacle for discarded cigarettes, ashes, etc. in which the element illustrated in Figs. 3 and 4 is used.

While the following description and accompanying drawings illustrate the principles of the invention, it is subject to many modifications, and is not limited to the forms selected for illustration, but only by the scope of the accompanying claims.

Referring to the details, and particularly to Figs. 1 and 2, the numeral 1 represents a part of a surface in which the apparatus, which, for convenience, may be called an ash receiver, is mounted. The part 1 may represent the front

wall of the instrument board of an automobile, the rear wall of the front seat of an automobile; or any other wall, or plate, forming part of a vehicle of any kind in which the device is mounted. 5 2 is the front wall and 3 the side walls of the casing in which the moving parts are mounted. This casing is open at the back and is pivotally mounted on the pin 4 to permit it to swing back and forth. It is shown in the open position. 10 When not in use, it is closed to a position wherein the top of wall 2 contacts the stop 6, and the working parts are concealed, while the walls 1 and 2 align to form a smooth surface. The knob 7 is for convenience in opening or closing the device. The waste-receiving tray 8, with knob 9, slides in or out on the stationary support 11, so that it may be removed for disposing of accumulated waste material.

Rotatably mounted within the casing is the 20 wheel 12 which is fixedly secured to the shaft 13. This shaft is reduced in diameter at the ends 19, and these ends are free to rotate in bearings formed in the side plates 3. Cavities 21 for extinguishing cigarettes are radially formed in the wheel 12. The diameter and depth of these 25 cavities are important. When cavities 21 are properly proportioned, a lighted cigarette, placed with the burning end down in one of them will be extinguished, due to lack of oxygen, in a period of approximately ten seconds. Suitable 30 dimensions of the cavities to accomplish this object are from three-eighths to one-half inch in diameter and five-eighths to three quarters inch in depth. The cavities are preferably bell-mouthed at the entrance, as shown, to facilitate 35 entering the cigarette, and each cavity accommodates only one cigarette at a time. Although the dimensions of the cavities may be somewhat varied, it is essential that the depth of the cavities be equal to or greater than the diameter, and the diameter must be small enough that a circulation of air within the cavity will not be produced by the heat of the burning tobacco. Thus, 40 each cavity serves as a confining station for extinguishing a lighted cigarette.

The shaft 13 has the ratchet 18 fixedly secured 45 to it, and on either side of the ratchet are the pendulum bars 17 which are supported upon the shaft 13 by hooks on their upper ends, as shown. 50 At their lower ends the bars 17 are joined together by the rivet 26 which passes through the pendulum weight 24, which is preferably made of lead. A pawl 27 is pivotally mounted upon the rivet 29, which, in conjunction with rivet 26 55 joins the pendulum parts into a unit. The pawl

is weighted as indicated at 28 to keep its point properly engaged in the teeth of the ratchet 18. The hooks of the pendulum bars engage the shaft 13 loosely so that it is free to swing whenever its equilibrium is disturbed by the motion of the vehicle in which it is mounted.

If the device is mounted on a vehicle, say an automobile, in such manner that the motion of the pendulum is parallel with the length of the car, the pendulum will be actuated by any marked change in speed of the vehicle, by changes in the grade, by bumps in the road, by starting or stopping, etc. If the device is mounted so that the pendulum is transverse to the direction of travel it will be actuated by transverse variations in grade, by curves in the highway, and even by such slight changes in direction as are often required to pass a vehicle.

The finer the teeth of the ratchet the more quickly the wheel will turn. A pitch of from $\frac{1}{32}$ " to $\frac{3}{4}$ " is satisfactory and the diameter of the ratchet may be approximately $\frac{1}{2}$ ". Other forms of a ratchet may be used in place of the type shown, if desired. A multiple pawl ratchet may be used if it is desired to increase the rate of rotation. The weight of the pendulum is not critical, but may be of the order of one to four ounces.

The wheel 12, which is actuated by the motion of the pendulum, moves intermittently and in uneven steps, depending upon the road, rate of travel, etc. Under usual driving conditions the wheel with six cavities will turn at a rate sufficient to give satisfactory automatic service, yet slowly enough that the discarded cigarettes are, with very rare exceptions, completely extinguished before being discharged.

Since the cigarettes are automatically extinguished for lack of oxygen when placed in the cavities 21, it is unnecessary to crush the burning end of the cigarette to put it out, as is commonly done by cigarette smokers to avoid the unpleasant odor given off by burning butts of cigarettes.

While the wheel 12 shows six cavities, wide wheels with two or more rows of cavities staggered or otherwise, may be provided, if desired.

Referring to Figs. 3 and 4, these show a modified form of wheel which may be used in place of the wheel 12 in Figs. 1 and 2. In this modification the wheel 41 is provided with longitudinal grooves or confining stations 42, which are of such width and length as to accommodate a cigarette lying horizontally in the groove, as indicated diagrammatically at 43. The grooves are preferably rounded at the bottom to conform more or less to the shape of the cigarette, and the width of the grooves may be from $\frac{1}{16}$ " to $\frac{1}{8}$ " wider than the diameter of an average cigarette. The grooves are therefore approximately $\frac{3}{8}$ " to $\frac{7}{16}$ " in width. With grooves of this size, cigarettes readily drop to the bottom of the groove, and are promptly discharged by gravity when the lower wall of the groove inclines downwardly.

Through the longitudinal axis of the wheel 41 is the hole 44, by means of which it is fixedly secured to shaft 46 (Fig. 5), upon which it is caused to rotate by a pendulum and ratchet mechanism (not shown in detail in Fig. 5) of the same design and construction as was described in connection with Figs. 1 and 2.

While the wheel 12 in Figs. 1 and 2 is arranged to rotate in counter-clockwise direction, due to the clearance required by the upstanding cigarette, the wheel 41 may be arranged to rotate 75

in either direction, but preferably clockwise, so that the empty cavities are more accessible as they emerge from the casing.

Referring particularly to Fig. 5, the casing which is triangular in cross-section, is pivotally mounted upon the pin 47 and the half bearing 48, so that the entire casing and attendant parts may be removed for emptying. 49 is the front wall of the casing which is provided with the knob 51 for convenience in opening and closing. The back wall 52 has fixedly secured to it the stop 53, which limits the outward motion of the casing when it strikes the bar 54. Bar 54 also limits the inward travel of the casing when the upper edge of the wall 49 contacts with it when the casing is in closed position. The ratchet and pawl are omitted from Fig. 5 as they are identical with similar parts in Figs. 1 and 2, with the exception that they are reversed to give the wheel 41 clockwise movement. The shaft 46, which supports the wheel 41, has reduced end portions similar to shaft 13 and these rest in the bearings in the side plates of the casing, which are slotted, as indicated, at 56, so that the wheel and attendant parts may be lifted out when it is desired to clean out the casing.

While the wheel 41 is incapable of rapidly extinguishing the burning cigarette, as does the wheel 12, it has been found that when a lighted cigarette is placed horizontally in a groove, as described, it gives off practically no smoke or disagreeable odor. The grooves 42 provide ample space for ashes, burnt matches, etc., which are automatically discharged into the receptacle below as the wheel rotates.

From the foregoing description it will be understood that the wheel 41 rotates automatically by the movement of the pendulum, and therefore serves as an ash receiver which is self discharging when mounted in any moving vehicle, the motion of which will cause the pendulum to function. The plates 57 and 58 virtually seal the space within the casing in such manner that there is no air circulation, and, therefore, practically no escape of smoke or unpleasant odor, even though the cigarettes may be discharged from the wheel before they are extinguished.

While either of the wheels 12 or 41 will revolve rapidly enough for all practical purposes through the action of the pendulum in a moving vehicle, they may be manually moved in the event that the vehicle is stopped, or if the movement of the vehicle should be so slight, at times, as to fail to discharge the cigarettes sufficiently often.

I claim:

1. Means for extinguishing cigarettes and receiving ashes and like waste matter comprising a casing; means adapted for pivotally mounting said casing on the wall of a vehicle; a shaft rotatably mounted in the opposite walls of said casing parallel to the pivot of said casing; a wheel with cavities, the latter having closed bottoms and at least one transverse dimension of approximately the diameter of a cigarette and being of greater depth than the diameter of a cigarette, adapted to receive discarded cigarettes mounted upon said shaft, said shaft being adjacent the top of said casing; a pendulum suspended from said shaft adjacent the axis of said wheel; a ratchet wheel operatively connected with said wheel; and a pawl carried by said pendulum adapted to engage the teeth of said ratchet wheel; whereby oscillatory motions of

said pendulum are translated into rotary motion of said ratchet wheel and connected parts, said casing housing said pendulum, pawl and ratchet wheel.

2. Means for extinguishing cigarettes and receiving ashes and like waste matter comprising; a casing; means for pivotally mounting said casing on the wall of a vehicle; a cigarette-extinguishing wheel with cavities of a size adapted to receive and extinguish discarded cigarettes; a mounting for said wheel comprising a shaft supported by a wall of said casing; a pendulum suspended from said shaft adapted to oscillate in response to inertia impulses produced by the motion of the vehicle; a ratchet-wheel operatively connected with said cigarette-receiving wheel; and a pawl operatively connected with said ratchet-wheel and pendulum, whereby oscillatory motions of said pendulum are translated into rotary motion of said ratchet-wheel 20 and cigarette-receiving wheel.
